DESIGN FOR A COMBINED DOORKNOB AND
ESCUTCHEON PLATE

Ina E. Petersen, Downey, Calif.

Application June 19, 1947, Serial No. 139,816

Term of patent 14 years

(Cl. D50—3)

To all whom it may concern:

Be it known that I, Ina E. Petersen, a citizen of the United States and a resident of Downey, California, have invented a new, original, and ornamental Design for a Combined Door Knob and Escutcheon Plate, of which the following is a specification, reference being had to the accompanying drawing, forming part thereof.

Referring to the drawing:

Figure 1 is a three-quarter side view of a combined door knob and escutcheon plate, showing my new design;

Figure 2 is a side elevation of the device;

Figure 3 is a front elevation thereof; and

Figure 4 is a section taken on line 4—4 of Figure 2.

I claim:
The ornamental design for a combined door knob and escutcheon plate, as shown.

INA E. PETERSEN.
